UNITED STATES PATENT OFFICE.

WALTER J. HAMMOND AND JOHN GORDON, OF RIO DE JANEIRO, BRAZIL.

RAILROAD-SPIKE.

SPECIFICATION forming part of Letters Patent No. 451,859, dated May 5, 1891.

Application filed July 29, 1890. Serial No. 360,267. (No model.)

To all whom it may concern:

Be it known that we, WALTER J. HAMMOND, a subject of the Queen of Great Britain, and JOHN GORDON, a citizen of the United States, 5 at present residing at Rio de Janeiro, Brazil, have invented a new and Improved Railroad-Spike, of which the following is a full, clear, and exact description.

The object of the invention is to provide a 10 new and improved railroad-spike which is simple in construction, securely holds the rails in place on the sleeper, and permits of a progressive driving in case it becomes loose in a sleeper.

15 The invention consists of a spike provided with a head having a beveled edge provided with a series of steps adapted to successively engage the edge of the base of the rail when the spike is driven farther in after having 20 become loose.

The invention also consists of certain parts and details and combinations of the same, as will be fully described hereinafter, and then pointed out in the claims.

25 Reference is to be had to the accompanying drawings, forming a part of this specification, in which similar letters of reference indicate corresponding parts in all the figures.

Figure 1 is a side elevation of the improvement. Fig. 2 is an edge view of the same. Fig. 3 is a side elevation of a pair of spikes as applied, the rail and sleeper being in section; and Figs. 4, 5, and 6 are perspective views of modified forms of the improvement.

35 A spike holds by the elasticity of the fibers of the sleeper immediately adjoining it. After a certain length of time these fibers lose their elasticity, and the hole made by the spike is enlarged permanently, so that the spike becomes loose and will finally work out. In order to give the spike a new hold in the sleeper, it becomes necessary to force it against a new set of elastic fibers, and if this cannot be done the spike becomes useless and must 40 be withdrawn and discarded. To avoid this and to permit of a progressing tightening of the spike in case it becomes loose is the object of the invention presently to be described.

The spike A is provided with a shank B, 50 pointed at its lower end and having a head C, one side D of which is formed with a beveled edge, in which are cut a series of notches E E' E² E³ E⁴, &c., as many as desired. The side F opposite the side D is formed with a 55 plain bevel, as is plainly shown in the drawings, the bevel preferably commencing somewhat below that of the side D, as is plainly indicated in Fig. 1. The shank B of the spike may be plain, as illustrated in Figs. 1, 2, and 60 3; or it may be provided with steps, as shown in Fig. 5, or with ridges or flanges, as illustrated in Fig. 4, or provided with grooves, as shown in Fig. 6.

In order to hold the rail G on the wooden 65 sleeper or tie H, the spike B is driven into the sleeper in the usual manner, but so that the first notch or step E engages the edge of the base of the rail G, as plainly shown in Fig. 2. Now when the spike becomes loose 70 in the course of time the operator drives the spike B again, so that the shank is caused to come in contact with new fibers in the wooden sleeper H, and at the same time the next following step E' engages the edge of the base 75 of the rail. By this means the spike B is again securely held in place as its shank is in contact with new fibers of the sleeper, and at the same time the beveled outer side F of the head of the spike securely presses 80 the new step E' in contact with the edge of the base of the rail. This operation of progressively driving the spike can be repeated as often as the spike becomes loose, so that the rail can be always held securely in place 85 on the sleeper H.

It is understood that when spikes such as shown in Figs. 4, 5, and 6 are driven the fibers, by their elasticity, always surround the steps or offsets or pass into the grooves, 90 so as to securely hold the shank B in place in the sleeper.

We are aware that spikes with single steps have been employed; but we do not, broadly, 95 claim such spikes.

Having thus described our invention, what we claim as new, and desire to secure by Letters Patent, is—

1. A railroad-spike provided with a head having a beveled side and provided with a series of steps adapted to successively engage the edges of the base of the rail when the spike is further driven after having become loose, substantially as shown and described.

2. A railroad-spike comprising a shank and a head formed on the said shank and having two oppositely-arranged beveled sides, one of the said sides being provided with a series of

steps or notches, substantially as shown and described.
